UNITED STATES PATENT OFFICE.

JOHN F. KEENAN, OF PROVIDENCE, RHODE ISLAND.

VALVE.

1,310,497.

Specification of Letters Patent.

Patented July 22, 1919.

Application filed April 10, 1919. Serial No. 288,904.

To all whom it may concern:

Be it known that I, JOHN F. KEENAN, a citizen of the United States, and resident of Providence, in the county of Providence and State of Rhode Island, have invented certain new and useful Improvements in Valves, of which the following is a specification.

This invention relates to improvements in the construction of discharge valves for flushing tanks, and the object of this invention is; first, to provide such a valve structure that may be readily fitted in a flushing tank by simply boring a round hole through the bottom thereof and setting up a nut beneath; second, to so form the valve structure that when mounted in the tank it sets so nearly flush with the bottom thereof that each time the tank is emptied all of the sediment will pass out and not be permitted to accumulate to soil the bowl.

A further object of the invention is to position the overflow discharge opening entirely within the periphery of the body of the discharge tube of the valve structure so as to obviate the necessity of further cutting away the bottom of the tank for the reception of the overflow discharge opening.

With these and other objects in view, the invention consists of certain novel features of construction, as will be more fully described, and particularly pointed out in the appended claim.

In the accompanying drawings:

Fig. 1— is a sectional elevation of the flushing tank, showing my improved valve structure mounted therein.

Fig. 2— is an enlarged sectional side elevation of the body portion of the valve structure, showing the same as applied to the bottom of a tank, which latter is shown in dotted lines.

Fig. 3— is a top view of the valve structure.

Fig. 4— is a sectional view of the valve structure on line 4—4 of Fig. 2.

Referring to the drawings, 10 designates the flush tank proper which is used in connection with water closets and the like, which tank may be constructed of any suitable material such as porcelain, cast iron, or metal-lined wood, but whatever its construction it is found in practice very desirable that the opening through the bottom of the tank shall be circular and of a standard size, so that when a correspondingly sized valve

structure is placed therein it may be readily drawn tightly by an outside binding nut to prevent leakage.

To accomplish this in a simple and effective way, I have provided a valve structure or seat portion which has a tubular member 11 circular in shape and adapted to extend through the bottom of the tank 12 from the inside outwardly and is provided on its inner edge with a very thin annular flange 13 under which is placed a thin packing washer 14 to set against the inner surface of the bottom of the tank.

One of the features of this construction is that the overflow discharge opening 15 is formed within the outer periphery of the body member 11, the overflow pipe 16 being connected to an offset portion 17 leading by way of the channel 18 to the discharge opening 15.

In order to provide a seat 20 for the valve 19 which controls the main flushing discharge through this body portion, I have offset the center of this seat from the center of the body portion and so have provided both a main flushing opening and an overflow discharge opening within the diameter of the tubular body member 11, and yet the water passing through this main discharge 85 has a direct fall through the conducting pipe 21 below, which is of importance in order to produce the maximum flushing effect.

The outer surface of this tubular body 11 is threaded as at 21 and when positioned to extend through the bottom 12 of the tank, a nut 22 is screwed beneath it for the purpose of drawing the flange 13 down tightly against its packing on the inner surface of the tank forming an absolutely tight joint and that by the use of standard fittings.

It is found in practice that where the flange 13 is made so very thin that it is difficult to hold the body member from rotating while the nut 23 is being screwed up to bind the whole in position. Therefore to facilitate the holding of this member during the screwing action on the nut, I have provided an upwardly extending boss 24 on the upper surface of the flange 13 which serves as a fulcrum for one end of a lever 25, shown in dotted lines in Fig. 3, whereby the whole valve structure may be firmly held in position during the setting up of the nut. Then again this boss is found to be convenient to receive a refilling passage 28 which

is tapped at 26 for the reception of the threaded end of the refilling pipe 27, through which pipe a predetermined amount of water is permitted to pass for the purpose of refilling the bowl after having been flushed.

My improved valve seat member is extremely practical in construction and may be positioned in the tank with the expenditure of but the minimum amount of time and when positioned will be absolutely tight.

Among other advantages in this structure are first, that the flange is made so very thin that practically all of the water in the tank 15 is forced out at each flushing operation thereby preventing the accumulation of sediment to discolor the bowl. Another advantage of this thin flange is that when the water is drawn off from the plumbing system to prevent freezing there is not sufficient left in this tank to freeze and damage the same, but just sufficient moisture remains in the tank to preserve the effectiveness of the packings.

Then again by my improved construction 25 the overflow outlet leads to a point below the valve seat wholly within the outer circumference of the outer portion of the valve seat structure thus eliminating the necessity 30 of cutting away any portion of the tank proper in order that the same may be positioned therein.

Copies of this patent may be obtained for five cents each, by addressing the "Commissioner of Patents, Washington, D. C."

The device is extremely simple and practical in construction and effective in its operation and by its use a new valve seat structure may be positioned with great ease and with the minimum expense.

The foregoing description is directed solely toward the construction illustrated, but I desire it to be understood that I reserve the privilege of resorting to all the mechanical changes to which the device is susceptible, the invention being defined and limited only by the terms of the appended claim.

I claim:

In a flushing tank, a valve structure having a circular, tubular body adapted to extend through the bottom of the tank, said body having a thin annular flange seated against the inner surface of the bottom of the tank, said body being provided with an overflow discharge opening located entirely within its circular body, a valve seat formed within said body offset from the center thereof, and an upwardly projecting leverage lug on said flange located at a point substantially opposite the overflow inlet, said lug being provided with a channel through it leading into the discharge pipe at a point below the valve seat, said channel being adapted to receive an after-fill tube in its upper end.

In testimony whereof I affix my signature.

JOHN F. KEENAN.
